UNITED STATES PATENT OFFICE.

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA.

ELECTRICALLY-CONTROLLED DOOR-OPERATING APPARATUS.

Application filed January 6, 1926. Serial No. 79,595.

This invention relates to apparatus for operating doors on street, subway and elevated cars, busses or the like. The object of the invention is to provide apparatus of 5 this nature which is simple in structure, efficient in operation and economical of manufacture.

A further object of the invention is to provide mechanical electrical control of door 10 operating motors of the pneumatic type and which permits conjoint control by the passengers and the motorman, conductor or other attendant on the vehicle.

Further objects of the invention will appear more fully hereinafter.

The invention consists substantially in the construction, combination, location and relative arrangement of parts, as well as the circuit arrangement and equipment employed 20 in connection therewith, all as will be more fully hereinafter set forth, as shown in the accompanying drawings and pointed out in the appended claims.

Referring to the drawings:

Fig. 1 is a view in front elevation showing the door operating and control apparatus embodying my invention.

Fig. 2 is an enlarged fragmentary view showing an end view of the door operating 30 motor and door support.

Fig. 3 is a sectional view taken on the line 3—3, Fig. 1.

Fig. 4 is a diagrammatic view showing the wiring connections employed in accordance 35 with my invention.

Fig. 5 is a sectional view of the treadle switch employed in accordance with my invention.

Fig. 6 is a side view of the same.

Fig. 7 is a sectional view of the door control switch employed in accordance with my invention.

Fig. 8 is a side view of the same.

Fig. 9 is an elevated view of the key operated street collector's switch employed in accordance with my invention.

Fig. 10 is a front view of the same.

The same part is designated by the same reference characters wherever it occurs 50 throughout the several views.

In my copending application, Serial No. 80,229 filed January 9, 1926, I have shown

several constructions of so-called "one man control vehicle" with conjoint treadle control of the door operating apparatus. In 55 such equipment means are provided for the one operator of the vehicle who for convenience may be called the motorman, whereby he may conveniently control and operate the doors of the vehicle so as to permit ingress and egress of passengers, and whereby, operating through pressure to the door engines, is conjointly controlled by a handle conveniently positioned adjacent to the motorman's station, and a treadle or deppressible platform at or near the exit doorway, upon which the passenger desiring to leave the car is compelled to stand or step upon. In this way, the motorman, in bringing his car to rest, manipulates a lever and if a passenger 70 under such conditions is standing or steps upon the treadle, a fluid pressure is admitted to the door engine whereby the latter becomes operative to open the door and lower the step. Furthermore, means are provided 75 for retaining the door and step in their open position as long as a passenger is standing upon either the treadle or the step. As a safety feature, means are provided whereby the door may not be opened by a passenger standing on the treadle unless the brakes are applied; i. e., the car is at rest. In my copending application, however, the control of the door engine is effected mechanically by means of levers, links, bell cranks and the 80 like.

Inasmuch as the control of pneumatic engines for operating doors has now been highly developed electrically, whereby electrical control of the fluid pressure by means 90 of magnet valves and the like, it is among the special purposes of my present invention to accomplish the same results by means of electrical as distinguished from straight mechanical control of valves which in turn control the supply of fluid pressure to and from the door engine.

Referring to Fig. 1, therefore, I provide doors 2—2 which are mounted on shaft 4 by means of plate pieces 5. The doors are hinged together as at 6. The step tread 9 is secured to the brackets 10 which are mounted on shaft 11 for rotation with it in the bearings 12 mounted on the car frame 12a.

It should be remembered that in Fig. 1 we are looking into the car from one side so that we see the inside of the doors, etc. A spring 13 is mounted on shaft 11 with end 14 secured to the bearing and end 15 secured to step tread 9 at 16. The point of attachment 16 will be on the far side or under side of the step tread 9. The arms 10 extend downwardly at 94 and are rigidly joined together by bar 95 for a purpose to appear hereinafter. In the car floor 96 is a rectangular opening 20 framed by angle irons 21 within which is mounted a treadle plate 22 flush with the floor 96. The plate 22 is hinged at 23 (Fig. 3) near the end furthest from the door as before described. Mounted on the car frame 12^a directly under the forward depressible end of plate 22 is a door control switch 97 having a vertical plunger 98 pressed upwardly by a spring in the casing 99. The upper end of plunger 98 contacts with the under surface of the treadle plate 22 and on the lower end of plunger 98 is an insulated contact making plate 100 for completing an electric circuit between contacts 101 and 102. Mounted for sliding in projections 103 and 104 is a rod 105 which engages a short pivoted lever 106 pivotally attached to the casing 99. The lower end 107 of rod 105 engages an angle plate 108 mounted on the bar 95.

Referring now to Fig. 4 showing the circuit connections of the electrical treadle control, contact terminal 101 is connected by a wire 109 to the magnet valve 110 of the well-known type which controls the valve 111 by the door engine 3. The other terminal 112 of magnet valve 110 is grounded to the car frame. Wire 113 goes from contact terminal 102, to the motorman's push button control switch 114 which will be described in detail later. Wire 113 is attached to terminal 115, and wire 119 shunts the contacts 116, 117 and 118. The contact 120 is connected to the positive side of the power source by lead 121. The wire connection 122 connects contact 123 with lead 109. At 124 is shown a street collector's switch, which will be described in detail later, a lead 126 connected to lead 109 and a lead 127 connected to the positive side of the power source.

In Figs. 5 and 6 is shown in detail the treadle controlled switch 97 with the projections 103 and 104 in which rod 105 slides. The lower end 107 contacts with angle plate 108 on bar 95 which is bolted to projections 94 of step arms 19, as before described. The upper end of rod 105 contacts with pivoted lever 106 mounted on the short pin 128 in brackets 129 mounted on projections 103. The other end of the lever 106 is fastened to casing 99 which in turn is keyed to rod 98. The rod 98 is secured to the U-shaped bracket 130 by nuts so as to move up and

down with treadle plate 22 since the U-shaped bracket is bolted to it. A coiled spring 131 encircles rod 98 within the casing 99 and a cup shaped projection 132 on box 97 so that the casing 99 is forced upwardly. The lower end of rod 98 has secured to it an insulated contact plate for closing the circuit through contacts 102 and 101 mounted on the insulating block 133. The leads 109 and 113 are connected respectively to contacts 101 and 102. Thus when a passenger steps on the plate 22 rod 98 slides downwardly closing the circuits between contacts 101 and 102. The lead wires enter box 97 through pipe 134.

The motorman's push button control switch 114 is shown in detail in Figs. 7 and 8. In the casing 114 are the push buttons 135 and 136 with horizontal rods 137 and 138 which are not in alignment (see Fig. 8). An insulated contacting disc 139 is mounted on rod 137 which closes the circuit between contacts 115 and 116 when the button 135 is pushed over against the action of a spring in casing 140 similar to spring 141. On rod 138 is another insulated contacting member 142 which closes the circuit between contacts 117 and 123 when push button 136 is pushed over against the action of spring 141. 143 is a pumper for connecting contacts 116 and 117 permanently together. At the bottom of the casing 114 is a small depending cylinder 145 in which a piston 146 moves upwardly against the action of spring 147 when air is admitted behind the piston through the threaded thimble 148. When the motorman moves the handle of control valve (not shown) to brakes applied position, the pressure in the brake air line is admitted behind the piston 146 so that the piston and connected rod 149 are forced upwardly. Rigidly secured to rod 149 is a disc 150 which closes the circuit through contacts 118 and 120. All the contacts 115, 116, 117, 119, 120 and 123 are mounted on blocks 110 of insulating material 144. The lead 119 is shown connecting contacts 116 and 118. The inner ends of push button rods 137 and 138 project into a casing or collar 151 having a depending projection to which the upper end of rod 149 projects. A thimble 152 fits over the end of rod 149 and a spring 153 is mounted in the thimble between it and the rod 149. A head of rubber, fibre or other friction material 154 is attached to the thimble 152, and is forced upwardly between rods 137 and 138 when pressure is applied to the piston 146 so that either push button will be held in depressed position as long as the brakes are applied. 155 is the point of entrance for lead wires 113, 121 and 122.

In one man car equipment it is frequently desirable to have at terminal stations, such as at a train or at subway stations at which a passenger vehicle discharges a great

number of passengers at one time, to afford the services of a street collector of fares. In other words, inasmuch as the motorman himself is the sole attendant on the vehicle must collect fares from his passengers and make change where necessary, it is obvious that if a large number of passengers are to leave the vehicle at any one station, a great loss of time would be occasioned by the necessity of all of the passengers leaving the vehicle one at a time by the conductor. For this reason it has been customary to provide at such terminal stations an additional attendant whose sole function is to collect fares; and to make it possible for the motorman or the attendant to open the rear door of the vehicle either independently of the control of or conjointly with the control of the rear door by the motorman so that when the motorman brings the car to a stop, and opens the front door through which the passengers at one end of the car may exit, the street collector may be accorded means for opening the rear door of the car and maintain this door open so as to permit passengers to pass through the rear door of the car past the street collector who collects the fares of such passengers. The street collector's switch hereinbefore mentioned is provided for this purpose.

Now, referring to Figs. 9 and 10 which show the street collector's switch 124 in detail, 156 is the key or switch handle which is adapted to be pushed into place on the rotatable shaft 157 from the outside of the car wall 158. 159 is a drum of insulating material mounted on shaft 157 for rotation with it. The end of the shaft 157 is formed D-shaped where the handle 156 is slipped on as at 160. On the ferrule 161 is a projection 162 for entrance into a U-shaped notch 163 in the car wall 158. This prevents the key 158 from being removed until strip 164 is out of contact with spring fingers 165 and 166. On the drum 159 is a contact strip 164 which engages to spring fingers 165 and 166 mounted on an insulating block 167, thus closing the circuit between leads 126 and 127 when the drum is rotated. The wires 126 and 127 are soldered to the lugs 168 and 169 respectively. 170 are brackets for mounting switch 124 on the inside of the car wall 159. In the collar 171 are detents 172 into which a spring pressed plunger 173 is forced so that the drum can only be turned between the two detents holding the drum 159 and strip 164 in either operative or inoperative position.

The operation of the electric treadle control modification will now be described. When the motorman applies his brakes and brings the car to rest, the air line pressure is applied to piston 146 which causes contacts 118 and 120 to be closed. The motorman then depresses push button 135 which closes the contacts 115 and 116. From then

on the operation is automatic due to the weight of the passenger on treadle plate 22 forced downward at its free end. The depression of plate 22 causes plunger 98 to descend and close contacts 101 and 102 through the contact disc 100. The current then passes from the positive pole of the power source through lead 121, contact 120, disc 150, contact 114, lead 119, contact 116, disc 139, contact 115, lead 113, contact 102, disc 100, contact 101, lead 109, and then through magnet valve 110 to ground lead 112. The valve 111 then admits air to the door engine 3 which opens the doors 2, 2 in the well known manner. When the passenger alights on step 9 which opens through the operation of the system of levers and cranks disclosed in the other modification of this invention, the control disc 100 of switch 97 remains in contact with terminals 101 and 102 through the agency of the plate 108, plunger 105 and lever 106 causing the rod 98 to remain depressed. When the step is cleared, the spring 13 turns step 9 upward thus freeing spring 131 of the treadle switch which causes the plate 22 and rod 95 to move upward opening the circuit at contacts 101 and 102. When the current is thus cut off, the magnet valve 110 admits air to the other side of the door engine piston in a well known manner to close the doors. The motorman then exhausts the air in the brake air line thus freeing the piston 146 as well as the brakes. The spring 147 then forces the disc 150 away from contacts 118 and 120, and the apparatus is reset for operation. It will thus be seen that the doors cannot be opened by a passenger standing upon the treadle plate 22 until the brakes are applied. If the motorman wishes to open the door himself with or without some one standing on the treadle plate, he need only depress button 136 after the brakes are applied, and the current will pass from the positive source of the current through lead 121, contact 120, disc 150, contact 118, lead 119, contact 117, disc 142, contact 123, lead 122, lead 109 and through the magnet valve 113 to ground lead 117. It will be noted that when the piston 148 is moved upward with the application of the air brake pressure, the friction head 154 on piston rod 149 is forced between the push button rods 137 and 138 to prevent the spring 141 from forcing the push button outwardly until the pressure in the brake air line is released.

When the street collector wishes to open the doors from the outside, he merely inserts key 156 in place, and rotates the drum 159 and contact plate 164 to the right until plunger 173 stops it. The current then passes from the positive terminal of the power source through lead 127, contact finger 165, contact strip 164, contact finger 166, leads 126 and 109 to the magnet valve 130.

110 and the ground lead 112. The rear door then opens. To close the door it is only necessary to rotate strip 164 out of contact with the fingers 165 and 167.

5 While I have thus illustrated and described certain embodiments of my invention, I do not wish to be understood as intending to limit it thereto, as the invention may be embodied in other constructions, and those 10 shown and described may be variously modified and altered without departing from the spirit of my invention.

I claim:

1. In a vehicle having entrance and exit 15 ways, barrier means for said ways, electrically operated means operable by the act of a passenger when the brakes are applied for opening the barrier means.

2. In a vehicle having entrance and exit 20 ways, barrier means for said ways, means operable by the act of a passenger for opening said barrier means, a treadle plate, a switch operable by said treadle to energize said door opening means and automatic means for closing said doors, when the passageways are cleared.

3. In a vehicle having entrance and exit 25 ways, barrier means on said ways, means for opening said barriers when the brakes are applied comprising a treadle, a treadle operated switch, a push button switch and current connections for energizing said barrier opening means.

4. In a vehicle having entrance and exit 30 ways, barrier means for said ways, means for opening said barriers when the brakes have been applied comprising a push button switch operated by the fluid pressure in the air brake line to energize said barrier opening means.

5. In a vehicle having entrance and exit 35 ways, barriers for said ways, means operable by the act of a passenger for opening said barriers when the brakes are applied, comprising a treadle plate, a plunger switch mounted under said treadle for operation when said treadle is depressed, a push button switch operated in part by the fluid pressure in the air brake line and in part by the operator, a magnet controlled door engine and automatic means for closing said barriers when said ways are closed.

6. In a vehicle, entrance and exit ways, barrier ways for said ways, means actuated by an act of a passenger for opening said barriers and independent means for opening said barriers from a position exterior to the vehicle.

7. In a vehicle having entrance and exit 40 ways, barriers for said ways, means operable by an act of a passenger for opening said barriers when the brakes are applied and independent means for opening said barriers from a position external to the vehicle.

8. In a vehicle having entrance and exit 45 ways, barriers for said ways, means operable by a passenger for opening said barriers and independent electrical means for operating said barriers from a position external to 50 said vehicle.

9. In a vehicle having entrance and exit 55 ways, barrier means in said ways, means operable by an act of a passenger when the brakes are applied for opening said barriers, and independent electrical means external to 60 said vehicle for energizing said means for opening said barriers.

10. In a vehicle having entrance and exit 65 ways, barrier means for said ways, means operable by an act of a passenger for opening said barriers, and independent means operable by the motorman to open said barriers.

11. In a vehicle having entrance and exit 70 ways, barriers for said ways, means operable by an act of a passenger when the brakes are applied for opening said barriers, and independent electrical means for energizing said means for opening barriers operable by said motorman from the interior of 75 said vehicle.

12. In a vehicle having entrance and exit 80 ways, barriers in said ways, means operable by an act of a passenger when the brakes are applied for removing said barriers, electrical means in the car for independently moving said barriers, and independent means accessible from the outside of said vehicle for energizing said means for moving 85 said barriers.

13. In a vehicle having entrance and exit 90 ways, barriers for said ways, means operable by the act of a passenger for opening said barriers comprising a hinged treadle 95 plate in said ways, a plunger switch mounted under said treadle so that it closes its associated circuit when the treadle is depressed, a step, means on said switch and said step for maintaining said barriers open 100 when the last passenger descends to the step, and automatic means for closing said door and step when the step is clear.

14. In a vehicle having entrance and exit 105 ways, barrier means for said ways, means operable by an act of a passenger when the brakes are applied for opening said barriers comprising a magnet operated valve, a pneumatic door engine, a treadle plate, a switch mounted under said plate so that on depression of the plate said switch is closed, a push button switch having a piston and switch blade on the rod so arranged that the switch blade closes the magnet valve by reason of the piston being subjected to the 115 fluid pressure in the air brake line, said push button switch having two buttons, one button cooperating in the associated circuits with the plunger switch to complete the magnet valve circuit, said piston also hav- 120 ing a piston rod having a stop 125 and a piston rod stop 130.

- ing means on it for frictionally holding said push button depressed and automatic means for closing said barriers when said ways are cleared.
- 5 15. In an electrical door opening system, a treadle controlled switch, a motorman's push button switch, a magnet valve controlled door engine and circuit connections for said devices.
- 10 16. In an electrical barrier controlling system for vehicles, a treadle plate in the platform of the vehicle, a switch mounted under said treadle plate, means operated by the motorman for completing an electrical circuit to a magnet valve controlled door engine.
- 15 17. In a semi-automatic barrier controlling system for vehicles, entrance and exit ways in the vehicle, barriers for said ways, electrically operated means for opening said barriers, a treadle operated switch, means operated by the motorman for putting said electrically operated means under control of the treadle switch, and means for holding said motorman's operated switch in operative position while the brakes are applied, and circuit connections for said device.
- 20 18. In an electrical treadle control barrier operating system, a push button switch, a treadle plate, a plunger switch mounted under said treadle plate, an electrically controlled magnet valve door engine, circuit connections for said devices, said push button switch being arranged to operate the barrier means independent of said treadle.
- 25 19. In an electrical treadle control barrier operating system, a push button switch, a treadle plate, a plunger switch mounted under said treadle plate, an electrically controlled magnet valve door engine, circuit connections for said devices and means accessible from the exterior of the car for independently opening the barriers.
- 30 20. In an electrically operated door opening system, door operating means, motorman controlled electrical means and passenger controlled electrical means for energizing said door operating means for opening the doors, said means acting conjointly to complete the circuit of said electrical means.
- 35 21. In a one-man controlled vehicle, entrance and exit ways, barriers in said ways, means for operating said barriers and electrical means actuated by an act of a passenger for energizing said means for opening said barriers.
- 40 22. In a one-man controlled vehicle, entrance and exit ways, barriers in said ways, a pivoted treadle plate in said vehicle, means for opening said barrier and independent means operated from the exterior of said vehicle for independently opening and closing said barriers.
- 45 23. In a one-man controlled vehicle, entrance and exit ways, barriers in said ways,
- a treadle pivoted in the platform of said vehicle, a switch mounted under said treadle, a motorman's push button switch, a magnet control valve operated pneumatic door engine, circuit connections for said devices, and means operated by the brake line, fluid pressure for holding said push button in operative position while the brakes are applied.
- 50 24. In a one-man controlled vehicle having entrance and exit ways, barriers in said ways including a step, electrical means for opening said barriers including a switch, means on said step, for holding said switch in closed position as long as a passenger remains on said step.
- 55 25. In a plunger switch, a casing, a plunger rod mounted in said casing, and means operated by said rod for contacting with a plurality of contact points.
- 60 26. In a switch, a casing, a hollow extension in said casing, a rod slidably mounted in said casing and said extension, a cap on said rod enclosing said extension, a spring encircling said rod and mounted in said extension and circuit closing means mounted on said rod.
- 65 27. In a switch, a casing having a U-shaped bracket mounted on said casing, a hollow extension on said casing, a slidable plunger rod extending through said casing and hollow extension, a spring encircling said rod within said hollow extension, a hollow cap mounted on said rod and sliding over said hollow extension, a vertical rod slidably mounted on said U-shaped bracket, pivoted means connecting said cap and said vertically slidable rod, and circuit closing means in said plunger rod.
- 70 28. A push button switch comprising a casing, a plurality of plunger rods terminating exteriorly of the casing in buttons, means for holding said rods in depressed position, and circuit making means on said rods.
- 75 29. A push button switch comprising a casing, a hollow extension on said casing, a vertically slidable rod in said extension extending into said casing, a circuit closing means on said vertical rod, a piston on said rod slidably mounted in said extension, a plurality of push button plungers in said casing, circuit closing means on said plungers, and friction means on said vertical rod arranged to frictionally engage said plunger rods.
- 80 30. In a drum switch, a casing, a rotatably mounted drum in said casing, a key mounted on the shaft of said drum exteriorly of said casing, a plurality of fingers in said casing and means on said drum for closing an electrical circuit between said fingers.
- 85 31. In a drum switch, a casing, an insulated drum mounted in said casing for rotation, means on said drum for closing an electrical circuit, a key for rotating said

drum and means on said key for preventing its application on removal from the shaft of said drum except when the drum is in circuit open position.

32. In a one-man controlled vehicle having entrance and exit ways, barriers in said ways, electrical means operable by an act of a passenger for opening said barriers, electrical means operated by the fluid pressure in the brake line for closing the circuit to said electrical means whereby said barriers cannot be opened until the brakes are applied.

33. In a vehicle having entrance and exit

ways, barriers in said ways, a fluid pressure operated switch, a treadle plate, a plunger switch mounted for operation by said treadle, a push button switch mounted with respect to said fluid pressure switch so that when the brakes are applied, said fluid pressure switch is closed and said push button switch is maintained in depressed position by said fluid pressure switch until the brake pressure is relieved.

In testimony whereof I have hereunto set my hand on this 30th day of December

A. D. 1925.

PARIS R. FORMAN.
